JAMES W. BRYCE, OF BLOOMFIELD, NEW JERSEY, ASSIGNOR TO THE TABULATING MACHINE COMPANY, OF ENDICOTT, NEW YORK, A CORPORATION OF NEW JERSEY

RECORD-CONTROLLED MACHINE

Application filed February 14, 1925. Serial No. 9,177.

This invention relates to improvements in record-controlled machines such as tabulating machines and more particularly is directed to the provision of means whereby the 5 control of the record designating means may be secured in a multiplicity of columns from and by perforations disposed in a single column of the record.

The invention may be best understood by 10 considering a regular Hollerith card and tabulating machine. Such a card usually has 12 index point positions in a column the normal lower 10 position designating values from 9 to 0 inclusive. Above there are two extra index 15 point positions usually called the eleventh and twelfth positions. Adding is usually only effected from the 9 to 1 positions inclusive, and all amounts derived from one column upon the card add into a particular 20 column upon the accumulator.

Occasions sometime arise when it is desired to secure greater adding or record designating capacity as regards columns than the capacity of the card will admit. For example, 25 there may be only three columns upon the card available for adding or designating certain items. It may happen that some of these items run in value over 999. Such amounts obviously require over three record 30 card columns. According to the present invention I utilize the upper extra hole positions in the card for securing additional column capacity. For example, an extra hole punched in the eleventh position of one column with the usual or normal perforations 35 designating 999 would designate an item amount of 1999. Similarly an extra hole in the twelfth position with index perforations 999 would designate amounts of 2999. According 40 to the present invention provision is made for handling such records and for effecting additions or other record designating operations in a greater number of columnar positions than there are in the record from 45 which the items are derived. Provision is also made whereby the extra amounts may be entered in any desired column upon the record-controlled devices.

The drawing shows my invention in dia- 50 grammatic form.

The invention is here shown as applied to a simple adding tabulator but it will be understood that the invention is not limited in its application to such adding tabulators as it may also be applied to printing tabulating 55 machines.

The record-controlled machine here shown is a tabulating machine having the usual card feeding devices, driving motor and controlling circuits. For convenience I have shown 60 at A an accumulator or register having various controlling elements such as magnets 12 coordinated to various orders or columns. While the magnets 12 are here conventionally illustrated as accumulator controlling means 65 it is obvious that such magnets or others may also be employed to control printer elements in a manner well known in the art. Hereinafter the magnets will be broadly designated as record designating means, which term is 70 intended to embrace the control of register or accumulator elements, printing elements or other devices such as visual indicators. The sensing means for the normal index point perforations comprises brushes and contact 75 blocks 10 which are connected to the plug-board sockets 11, 11^a, 11^b, etc., in the usual manner. Magnets 12 are connected to sockets 13, 13^a, 13^b, etc. For sensing the extra index point perforations I provide extra brush 80 and contact means 14 here shown as a single brush. There may be a row of these brushes if desired or a single brush may be arranged to be slidable to different columnar positions.

For purposes of illustration it will be assumed that the brush is in alignment with the column containing perforations at the 2 and eleventh positions. Plug socket 11 is connected to brush 10 aligned with the first column and plug connection is made from 85 11^a to socket 13^a. For the next column, plug connection is made between socket 11^b and 13^b. The socket marked 13 is reserved for the extra items. A plug connection 15 is inserted in socket 13. 90

It will be understood that the brush sensing device 14 will establish contact through index point perforations in either the eleventh or twelfth positions before brush 10 enters the No. 2 index point perforation. The extra 95 100

brush 14 receives current from a line 16 extending to right side of line 27, which circuit also includes card lever contacts 16^a to close this supplemental brush circuit only while 5 cards pass through the machine. From the supplementary sensing means 14 a wire 17 leads to a commutator 18 driven in unison with the card feed and having two segments 19 and 20 adapted to establish contact with 10 brush or wiping contact members 21 and 22, respectively, at the time the 11th or 12th index point position is under brush 14. Assuming a hole at the eleventh position, as shown, current will flow from 17 to 18 to 19 to 21 15 through wire 23 to relay 24, energizing the relay and flowing to left side of line 35 through contacts 26 now closed and wire 36. The relay circuit is almost immediately interrupted both by brush 14 leaving the hole in the 20 card and by 21 passing off segment 19. Consequently a holding or stick circuit 28-29 is provided to right side of line 27 which maintains relay 24 energized until cam contacts 26 open and deenergize the relay. En- 25 ergization of the relay also establishes a circuit from right side of line 27 through 29, 30, 31 to cam contacts 32, which contacts are timed to close just at the period in the card cycle when the brushes 10 are over the "one" 30 index point position. Such contact closure permits the current to flow through the contacts 32 to plug connection 15 which is inserted in socket 13. Consequently the counter magnet for the record column is energized 35 so as to add one into the counter in the column position to the left of column in which 2 is added.

If it be desired to add two in the extra column the perforation would be made in the 40 twelfth position. The brush 14 would close the commutator circuit through 20, 22, energizing relay 24^a and establishing similar holding and extra circuit to contacts 32^a. These contacts are timed to close at the 2 index 45 point position thereby adding two on the extra column in the counter.

The purpose of contacts 26 is to interrupt the holding circuits to relays 24 and 24^a after these relays have held their respective circuits to contacts 32 and 32^a and permitted these contacts to initiate an adding operation, if such operation is called for. Thus the relays will be deenergized and ready to function again upon the next card cycle. It will 55 be understood that contacts 26 reclose at a time before the relays 24 or 24^a are to be re-energized if they are so to be upon the next card cycle.

With the arrangement disclosed it will be 60 apparent that an additional counter capacity of one column and representing one or two units may be secured. Thus it is possible to obtain additions of items of from 0 to 9 with one hole punched in a column and with two 65 holes punched depending upon the location

of the extra hole it is possible to enter items into the accumulator of from 0 to 19 or 0 to 29. With extra columns perforated in the normal way at the right of the column containing the double punching it is possible 70 to secure the entry of amounts such as from 0 to 199 or 0 to 299 as will be readily understood.

What I claim is—

1. A record-controlled machine having 75 multi-columnar record designating devices, record sensing means arranged to cooperate with perforations disposed in a single record card column, and to be effective for controlling from both perforations in a single 80 card reading and item entering cycle, said sensing means having provisions called into action upon the sensing of an extra perforation in the record card column for initiating the action of the record designating devices 85 pertaining to a different and extra column.

2. A record-controlled machine having multi-columnar record designating devices, record sensing means arranged to cooperate with perforations disposed in a single record 90 card column, said sensing means having dual perforation sensing means respectively cooperating with the normal and extra perforations in a single record card column upon a single presentation of a record card to the 95 sensing means in one card reading cycle, and means controlled by one of said dual sensing means for effecting control of the one record designating means pertaining to one column, and means controlled by the other of said record sensing means for effecting a control of the different distinctive and separate record designating means pertaining to another 100 column.

3. A record-controlled machine including 105 sensing means for the normal index point perforations and for extra index point positions, multiple column record-controlled devices controlled by said sensing means, each said device being independent of and separate from the others and each pertaining to a particular column, and means for controlling said devices to effect an operation of the same in one column from the normal index point perforations and to effect an operation 110 of the same in a different column from the extra index point perforations, said last mentioned means including devices brought into 115 operation upon a single card reading cycle for effecting the aforesaid operation in both 120 columns.

4. The invention set forth in claim 3 in which means is provided for selecting the column of record designating devices which are to be controlled by the extra index point 125 perforations, said means being selectively operable with the devices which enter the normal index point perforations into the record designating devices maintained in fixed relation to each other.

5. A record-controlled machine including a supplemental sensing means adapted to sense a supplemental extra perforation or perforations in a controlling record having 5 normal index point perforations in the same column thereof which are sensed and which effect an operative control in the same card reading cycle in which the supplemental sensing occurs, record designating devices 10 controlled in their operation by said supplemental sensing means, means for effecting various operations of said record designating devices in accordance with which extra perforation is sensed in the record, said last record designating means being wholly separate from and independent of and pertaining to a different column than the column controlled by the normal index point perforations of said controlling record.
- 20 6. A tabulating machine having an accumulator and provisions for sensing records with extra index point perforations disposed in the record columns containing the normal index point perforation, and means controlled by said extra index point perforations for effecting adding of amounts in columns of the accumulator other than those which receive the registry of the normal index point perforations from the same column during 30 the same adding cycle and card sensing cycle of the machine.
7. In a tabulating machine having accumulator devices, in combination with means for sensing records with extra index point perforations disposed in the record card columns which contain normal index point perforations, means controlled in accordance with the position of said extra index point perforations for controlling various adding 40 operations of said accumulator in columns thereof differing from those which receive the registry of amounts under control of the normal index point perforations during the same adding cycle and card sensing cycle of 45 the machine.
8. In a tabulating machine having an accumulator and means for sensing multiple perforations in a single column of a controlling record and effecting concurrent adding in a single adding cycle of the machine of the data represented by both perforations, said multiple perforations including normal perforations and extra perforations, and means for utilizing the extra adding capacity of the 50 accumulator by entering amounts therein derived from the extra perforations which are normally ineffective for controlling the adding.
9. In a tabulating machine having in combination record sensing means, accumulator controlling item entering devices corresponding to different denominational orders, and means controlled by the index point perforation sensing elements operating upon a common index point column for controlling ac- 60
- cumulator controlling item entering elements pertaining to a plurality of different orders in the same part of the machine cycle in which item amounts are entered for adding.
10. The invention set forth in claim 9 in which selective means is provided for controlling the order of the accumulator in which amounts may be entered, said means being supplemental to the perforation sensing means and operable with the perforation sensing devices in fixed relation to a record. 70
11. In a tabulating machine having sensing devices for sensing index point perforations disposed in a single record card column, said perforations including extra perforations additional to the normal register controlling index point perforations, said normal index point perforations controlling the normal and usual entry of numbers of from one to nine in a said register, a register 80 having various denominational order elements and means controlled in accordance with one or another extra index point perforation for entering one or another amount in said register. 85
12. The invention set forth in claim 11 in which means is provided for entering the said amounts in the register upon elements of other denominational orders than those receiving entries from the normal index point 90 positions. 95
13. The invention set forth in claim 11 in which means is provided selectively operable by the operator for controlling the order of elements which are to receive the extra means, 100 said selecting means being selectively operable with the devices which enter the ordinary items into the register maintained in fixed relation.
14. In a recording apparatus for handling record cards perforated in multiple columns with record designating means controlled by the perforations, sensing means for sensing said perforations, said sensing means including normal index point sensing means and extra index point sensing means, and means for selectively associating the extra sensing means with one of a plurality of the record designating means. 105
15. A record controlled apparatus including means for feeding perforated records, devices controlled in accordance with the perforations, means for sensing said records in motion, and for controlling the said devices, said sensing means including dual sensing elements arranged to traverse a common field of the record, and means associated with said sensing means for suppressing the designating effect of the normal index point perforations upon said devices, said means 115 which is associated with the sensing means becoming effective only upon encountering an extra index point perforation in the same record column. 120
16. A tabulating machine having an accu- 125

- mulator with record sensing means for sensing normal and extra index point positions, said means including a common sensing means for sensing either of a plurality of the extra index point positions, and means under the control of said common sensing means for entering extra items into an order of the accumulator other than that order receiving the normal entry.
17. A tabulating machine having an accumulator and record sensing means for sensing the normal index point positions of a record and for entering items into an accumulator in certain orders thereof, a common sensing means supplemental to the aforesaid sensing means for sensing either of a plurality of extra index point positions, means for entering into the accumulator in an order other than those receiving the entries from the normal index point positions items extra to those designated by the normal index point positions, and means for controlling the amount of said extra entry in accordance with the extra index points positions which is sensed by the aforesaid common sensing means.
18. A record controlled machine including sensing means for sensing record cards in motion, said sensing means including dual perforation sensing devices co-operating respectively with normal and extra index point positions, multiple column record controlled means controlled by said sensing means, and means for controlling said last named means during transitory movement of the records to effect an operation of the same in one column from the normal index point perforations and to effect an operation of the same in a different column from an extra index point perforation.
19. A record controlled apparatus with record designating means and a dual sensing means disposed in staggered relation relative to a record to cooperate with different portions thereof, means for synchronizing and timing the sensing of the perforations by said means and means controlled by the conjoint control of the dual sensing means and by the last mentioned means for controlling record designating devices.
20. The invention set forth in claim 19 with which means is provided for continuously feeding the record cards through the machine and in which the dual sensing means is adapted to sense the record cards when in motion.
21. A record controlled apparatus including designating means controlled by the records, perforation sensing means comprising a plurality of devices arranged to successively traverse the index points of a certain column upon the record and to control the operation of said devices and means for suppressing the control of the designating devices by the sensing means upon one sensing means trav-

ersing a certain portion of a record column.

22. A record controlled apparatus with record controlled designating means and a sensing means of dual form which are traversed successively by the index point positions of a column, and means for establishing controlling relation between one sensing means and the designating means only for certain positions of a column, and for suppressing said controlling relation for other positions of the column in which the other sensing means has controlling relations with the designating means.

In testimony whereof I hereto affix my signature.

JAMES W. BRYCE. 80

CERTIFICATE OF CORRECTION.

Patent No. 1,774,051.

Granted August 26, 1930, to

JAMES W. BRYCE.

It is hereby certified that error appears in the printed specification of the above numbered patent requiring correction as follows: Page 3, line 122, claim 15, after the word "with" insert the words one of, and line 125, for the word "devices" read device; and that the said Letters Patent should be read with these correction therein that the same may conform to the record of the case in the Patent Office.

Signed and sealed this 21st day of October, A. D. 1930.
